US0D1064469S

(12) **United States Design Patent** (10) Patent No.: **US D1,064,469 S**
(45) Date of Patent: ** Feb. 25, 2025

(54) **CLEANING MACHINE**

(71) Applicant: **TINECO INTELLIGENT TECHNOLOGY CO., LTD.**, Suzhou (CN)

(72) Inventors: **Wujia He**, Suzhou (CN); **Xuan Yu**, Suzhou (CN); **Xiangyu Yang**, Suzhou (CN); **Yongxiong Huang**, Suzhou (CN); **Song Mao**, Suzhou (CN)

(73) Assignee: **TINECO INTELLIGENT TECHNOLOGY CO., LTD.**, Suzhou (CN)

(**) Term: **15 Years**

(21) Appl. No.: **29/787,264**

(22) Filed: **Jun. 4, 2021**

(30) **Foreign Application Priority Data**

Dec. 21, 2020 (CN) 202030790111.3
Dec. 21, 2020 (CN) 202030790114.7

(51) **LOC (15) Cl.** **15-05**

(52) **U.S. Cl.**

USPC **D32/22**

(57) **CLAIM**

The ornamental design for a cleaning machine, as shown and described.

DESCRIPTION

FIG. 1 is a front perspective view of a cleaning machine, showing our new design;

FIG. 2 is a partial enlarged view thereof;

FIG. 3 is a front view thereof;

FIG. 4 is a left-side view thereof;

FIG. 5 is a right-side view of thereof; and,

FIG. 6 is a top view thereof.

The broken lines shown in the views depict portions of the cleaning machine that form no part of the claimed design.

1 Claim, 6 Drawing Sheets
